FREQUENCY MODULATED RECORDING AND
REPRODUCING SYSTEMChester M. Sinnett, Westmont, N. J., assignor to
Radio Corporation of America, a corporation of
Delaware

Application May 15, 1943, Serial No. 487,121

8 Claims. (Cl. 179—100.4)

1

My present invention relates to sound recording systems, and more particularly to a home recording system utilizing frequency modulation.

Home recording and/or reproducing of sound has been accomplished in many ways in the past. The ideal home recorder should be capable of producing a relatively inexpensive recording adapted to have a low noise level during reproduction. Frequency modulation has been utilized to translate sounds into mechanical recordings. The recorded impression corresponds in that case to a frequency modulation signal. One of the advantages of such a method of recording is the low noise level developed during record reproduction.

It can be stated that the main object of my present invention is to provide a home recording system employing a dielectric tape which has directly recorded thereon a frequency modulated signal.

Another important object of this invention is to provide a novel method of recording sound waves; the method including the steps of embossing on a dielectric record frequency modulation signals derived from the waves, frequency modulating a substantially higher frequency oscillation in accordance with the embossed recording, and subjecting the frequency modulated oscillation to successive discrimination to derive the original sound waves.

Another object of the invention is to provide a home recording device which uses low cost material, such as paper tape, for the recording medium, there being recorded directly on the paper tape impressions representative of frequency modulation signals, reproduction of the tape being provided by translating capacity changes, engendered by the tape impressions, into frequency modulation signals of a high mean frequency, and deriving from the last-mentioned signals the original sounds which were recorded on the tape.

Yet another object of my invention is to provide a relatively noise-free system of reproducing a sound record of the type wherein record impressions exist in a record medium of dielectric material; the system comprising an oscillator whose frequency is varied by virtue of variations in capacity of a condenser whose dielectric element consists of said record medium, the resulting frequency-variable oscillations being detected in any well-known manner to provide sound currents corresponding to the aforesaid impressions.

A more specific object of my invention is to improve reproduction of frequency modulation signals recorded on a medium made of dielectric

2

material; the recorded medium being employed as the dielectric element of a condenser composed of a metallic stylus and a metallic roller, there being provided in series with the condenser a second condenser employing said roller as an element thereof; the first condenser having a capacitance which is a relatively small fraction of the second condenser capacitance; and the series condensers being arranged across an oscillator operating at a relatively high radio frequency thereby to provide frequency modulated oscillations whose frequency deviations are essentially produced by variations in the capacitance of the first condenser due to the impressions of said record medium.

Still further objects of my invention are to improve generally the operation and fidelity of reproduction of home recording systems, and more especially to provide such a system in an economical, efficient and durable manner.

The novel features which I believe to be characteristic of my invention are set forth with particularity in the appended claims; the invention itself, however, as to both its organization and method of operation will best be understood by reference to the following description, taken in connection with the drawing, in which I have indicated diagrammatically several circuit organizations whereby my invention may be carried into effect.

In the drawing:

Fig. 1 shows schematically a recording system in accordance with my invention.

Fig. 2 is a magnified view of the "hill and dale" impression on the record tape.

Fig. 3 schematically represents the record reproduction system.

Referring now to the accompanying drawing, wherein like reference characters designate similar elements in the different figures, I have schematically represented in Fig. 1 a system for recording sounds in an economical manner. For example, in home recording, office recording and similar uses, it is often desirable to provide a readily-replaceable recording medium. In the past various forms of simple recording media have been proposed. The methods of recording have been diverse; certain of the methods have proposed the use of frequency modulated (FM) signals as the recorded waves. In this connection reference is made to my application Serial No. 463,349, filed October 26, 1942, for the disclosure of an improved system for translating sound waves into FM signals adapted to be recorded on any desired medium.

According to my present invention, the recording medium consists of a strip or tape of a dielectric material. Such a tape could be made of paper, Celluloid or any other material capable of being deformed or embossed by a stylus tip. Those skilled in the art are fully acquainted with the method of recording of sounds by employing a stylus to emboss the surface of a moving tape made of paper or Celluloid. Hence, it will be sufficient to represent the recorder or embosser in schematic manner.

The numeral 1 in Fig. 1 denotes a microphone of any desired form and construction adapted to translate sound waves, whether music or speech, into corresponding audio frequency currents. An oscillator 2, preferably operating at a frequency of 15 kilocycles (kc.), produces oscillations of constant amplitude. The oscillator mean frequency may, if desired, be higher or lower than 15 kc. The mean frequency (F_c) may be chosen from a range of the order of 10 to 50 kc. The oscillator frequency is deviated in accordance with the audio currents. That is, the oscillator 2 is subjected to frequency modulation. A so-called reactance tube 3 may be used to vary the oscillator frequency in accordance with the audio currents produced at the microphone output terminals.

The reactance tube circuit may be of any well-known form. Since those skilled in the art of FM are fully cognizant of the circuit details, it need only be explained that the reactance tube simulates or provides a reactive effect. The latter is used to vary the oscillator frequency, since the tube gain is varied in response to audio current amplitude. The extent of oscillator frequency deviation is a function of audio current amplitude, while the rate of deviation depends on the audio frequencies per se. A maximum deviation up to 3 kc. on each side of F_c may be utilized. The invention is not restricted, however, to such deviation frequencies, nor is it restricted to the specific mean frequency range of 10 to 50 kc. referred to above.

The FM oscillatory output of oscillator 2 is passed through an amplitude limiter 4 whose "input-output" characteristic is depicted above the limiter representation. Any desired form of limiter may be used to eliminate amplitude modulation effects that may exist on the output energy of oscillator 2. The band pass filter 5 provides rejection of carrier frequency swings exceeding 5 kc. from the illustrative mean or center frequency of 15 kc. The output energy at the output terminals of filter 5 is passed through an amplifier 6. Therefore, it will be seen that FM signals are supplied to the recorder device 7. The recorder may be of any well-known form, and is provided with a stylus 8 actuated by an energizing coil 8' fed with the FM signal output of amplifier 6. The stylus 8 functions as an embossing element to emboss on the tape 9 impressions corresponding to the signals.

Numerals 10 and 12 denote rollers adapted to guide the tape 9 over the roller 11. The impressions embossed, or engraved, on the upper face of tape 9 are of the "hill and dale" variety. That is to say, the stylus 8 is subjected to vertical reciprocation in response to the FM signal currents flowing through the energizing coil 8' of the recorder device. In Fig. 2 I have shown the contour of the impressions produced by embossing stylus 8 as the tape 9 rides over the roller 11. The impressions 9' are to be understood as being an exact physical representation of the FM signals. The impressions 9' will appear as shown

in Fig. 2, in cross section, at the center of the groove. Since the tape 9 is paper, which may be properly treated to provide satisfactory embossing, there is provided a cheap and simple form of record medium. It is to be clearly understood that in place of conventional FM systems there may be employed between audio source 1 and limiter 4 the FM system of my aforesaid application.

The reproduction of the embossed tape 9 is carried out, according to my invention, in a manner such that a minimum noise level is produced. To secure a noise-free reproduction the impressions 9' are translated into capacity variations. The latter are, in turn, translated into frequency variations of a high frequency oscillator. The resulting FM signal energy is then subjected to successive demodulations to produce the original sounds which were recorded. These steps are carried out by the system now to be described.

The tape 9 is guided over the face of a metallic roller 13 by the rollers 16 and 17. A metallic stylus 15 is pivotally mounted in the usual manner so as to permit the tip of the stylus to ride over the "hill and dale" impressions of the tape. Since the tape 9 is made of dielectric material there is provided a condenser consisting of the stylus 15, dielectric tape 9 and metal roller 13. The capacitance of this condenser is of variable value, and depends upon the variable thickness of tape 9. Hence the impressions 9' are translated into capacity changes. The variable condenser is, then, of the type wherein the dielectric is the varying element. A second condenser is arranged in series with the first condenser. The second condenser includes roller 13 as an electrode. The grounded convex metal plate 14 acts as the low potential electrode of the second condenser. Air is the dielectric between metal roller 13 and convex plate 14.

Merely by way of illustration it is pointed out that the capacitance (maximum) of condenser 15-9-13 may be of the order of 3 to 4 micro-micro-farads (mmf.). The second condenser 13-14 is given a much larger capacitance. For example, the condenser 13-14 may be of the order of 100 mmf. These series condensers are shunted across the tank circuit 18 of an ultra-high frequency oscillator 19. The latter may have a mean frequency of 30 megacycles (mc.). The specific construction of oscillator 19 is not material to my invention, nor is the particular oscillator frequency limiting in any respect. It is desirable to have the oscillator tank circuit 18 tuned to a normal frequency which is several times higher than the mean frequency of the recorded FM signals.

The frequency of tank circuit 18 will now be deviated, or modulated, in accordance with the capacity variations across the series condensers. Since the small variable condenser and large fixed condenser are in series, the effective capacitance across tank circuit 18 will be equal to the sum of the reciprocals of the separate condensers. Changes in the capacitance of the small variable condenser will, therefore, be a substantial portion of the total capacity effect across the tank circuit 18. The large fixed condenser 13-14 prevents the occurrence of electro-static noises which would arise from the use of a mechanical rubbing contact. By the use of capacity coupling as shown, a direct mechanical connection is not necessary.

It will be clear that the oscillations of oscillator 19 will be deviated a maximum of 30.18

mc. and a minimum of 30.12 mc. This follows from the fact that the signals recorded on the tape represent a 15 kc. oscillatory wave which is frequency deviated a maximum and a minimum of 3 kc. It will, therefore, be seen that the oscillatory output of oscillator 19 will actually be a modulated wave. In other words, the ultra-high frequency oscillations whose mean frequency is 30 mc. will be frequency modulated by a primary frequency modulation signal. This double modulation method of reproducing also tends to maintain a low noise level. The reason for double frequency modulation can best be explained by stating that if audio frequencies of the order of 15 kc. were used, the small capacity change caused by the stylus riding in the groove would not be sufficient to produce a frequency shift which could be later demodulated. By using a radio frequency a larger degree of frequency shift is obtained directly from the capacity variations caused by tape thickness, and in this way the superaudible frequency modulation signals recorded on the tape have sufficient amplitude to be again demodulated.

The frequency modulated output of oscillator 19 is subjected to the action of any well-known form of discriminator-rectifier 20 in order to derive therefrom the primary FM signals which were recorded on the tape 9. Above the rectangle 20 there is shown the typical and ideal S-shaped characteristic which is representative of the action of an FM detector. For example, there may be used for this detector the type of FM detector shown by S. W. Seeley in his U. S. Patent No. 2,121,103, granted June 21, 1938. The output of the network 20 is passed through a band pass filter 21 so as to eliminate any frequency deviations which are less than 10 kilocycles and more than 20 kilocycles. It will be recognized that the function here is similar to that described in connection with band pass filter 5 in Fig. 1. The filter 21 keeps out noise modulations below 10 kc. A high pass filter above 10 kc. would probably prove to be as satisfactory. If surface noise and other noises below 10 kc. are allowed to come through the system, then they will be reproduced in the audio output.

In order to eliminate any amplitude modulation effects which may have arisen, there is employed an amplitude modulation limiter 22. A second discriminator-rectifier 23 is then employed to derive the original modulation from the low frequency carrier. This network 23 may be constructed in the same manner as network 20. However, whereas network 20 may have a mean frequency of 30 mc., the network 23 will have a mean frequency of 15 kc. The modulation output of network 23 will be the audio frequency currents which existed at the output terminals of the microphone 1 in Fig. 1 at the time a particular record was made. Any desired type of audio frequency amplifier 24 may now be employed to amplify the audio currents. The amplified audio currents may then be reproduced by any well-known form of loud speaker or other sound reproducer.

It will be clearly understood that I have omitted from the schematic showings of Figs. 1 and 3 the specific driving mechanisms for actuating the tape 9. These are very well known, and are not deemed to be essential to a proper description of this invention. Furthermore, it will be clear that the tape 9 when provided in the form of rolls will be capable of considerable usage, and can be manufactured sufficiently

cheaply so as to warrant destruction of the tape when it has served its purpose. Further, the signals may be recorded directly on the film, or tape, at audio frequencies.

While I have indicated and described several systems for carrying my invention into effect, it will be apparent to one skilled in the art that my invention is by no means limited to the particular organizations shown and described, but that many modifications may be made without departing from the scope of my invention.

What I claim is:

1. In a capacity pickup device: a metallic stylus, a metallic support, a record consisting of a relatively thin tape composed of paper, a face of said tape being provided with a plurality of embossed impressions in the form of hills and dales, said tape being positioned to move between said support and stylus with the stylus riding in said impressions, and said impressions being representative of frequency modulation signals.

2. A method of recording sound waves which includes the steps of embossing on a dielectric recording medium frequency modulation signals derived from the sound waves, frequency modulating a substantially higher frequency oscillation in accordance with the embossed recording, and subjecting the frequency modulated oscillation to successive demodulations to derive the original sound waves.

3. In combination with an oscillator of relatively high mean frequency, means for modulating the oscillator comprising a pair of condensers arranged in series across the oscillator tank circuit, one of said condensers having a substantially smaller capacitance than the other condenser, a record made of dielectric material functioning as the dielectric of said small condenser, and one of the electrodes of the small condenser functioning as a stylus for impressions on the dielectric material.

4. A method of reproducing a record whose impressions corresponds to frequency modulation signals of a low mean frequency, translating the impressions into corresponding capacity variations, generating oscillations of a relatively high mean frequency, translating the capacity variations into deviations of said relatively high frequency oscillations, demodulating the resulting frequency-deviated oscillations to provide the recorded frequency modulated signals, and subjecting the frequency modulation signals to further demodulation to derive therefrom sounds corresponding to the modulation on the original frequency modulation signals.

5. In combination with an oscillator of relatively high mean frequency, means for modulating the oscillator comprising a pair of condensers arranged in series across the oscillator tank circuit, one of said condensers having a substantially smaller capacitance than the other condenser, a record made of dielectric material functioning as the dielectric of said small condenser, one of the electrodes of the small condenser functioning as a stylus for impressions on the dielectric material, and a metal guide roller acting as the common electrode for both condensers.

6. A method of reproducing a record whose impressions correspond to frequency modulation signals of a low mean frequency, translating the impressions into corresponding capacity variations, generating oscillations of a relatively high radio frequency, translating the capacity variations into deviations of said relatively high radio

frequency oscillations, demodulating the resulting frequency-deviated oscillations to provide the recorded frequency modulated signals, filtering the latter through a band pass network, subjecting the frequency modulation signals to further demodulation to derive therefrom sounds corresponding to the modulation on the original frequency modulation signals.

7. In combination with an oscillator of relatively high radio frequency of the order of 30 megacycles, means for modulating the oscillator comprising a pair of capacities arranged in series across the oscillator tank circuit, one of said capacities having a substantially smaller capacitance than the other capacity, a record made of dielectric material functioning as the dielectric of said small capacity, one of the electrodes of the small capacity functioning as a stylus for impressions on the dielectric material, and means for demodulating the oscillator output.

8. A method of reproducing a record whose impressions correspond to frequency modulation signals of a low radio frequency, translating the impressions into corresponding capacity variations, generating oscillations of a relatively high

radio frequency, translating the capacity variations into deviations of said relatively high radio frequency oscillations, demodulating the resulting frequency-deviated oscillations to provide the recorded frequency modulated signals, and deriving from the latter sounds corresponding to the modulation on the original frequency modulation signals.
